UNITED STATES PATENT OFFICE

2,561,570

ATOMIZER

Edward L. Hadden, Westfield, N. J.

Application March 8, 1947, Serial No. 733,266

4 Claims. (Cl. 299—88)

1

My invention relates to that class of devices designed to spray or atomize a fluid. Such a device is described in my application Serial No. 654,825, now abandoned, of which this is a continuation-in-part. More particularly it relates to the spraying of the nose or throat of a person. It is well known that the use of such medical means are clumsy, and in some cases offensive. Attempts have been made to overcome these objections, but only with partial success, as the proposed devices have one or more serious objections. For example, United States patent to Scott, No. 1,838,873, has that portion which is to be inserted in the nostrils, exposed at all times. Thus it will become contaminated by the mucus from the nasal passage, and by the spray employed. This condition is unavoidable, the result being that it is unsightly and the clothing of the user may be soiled.

My invention has for its principal object to eliminate these objections by providing for a complete enclosure of the tip except when actually in use thus insuring the production of a sanitary device.

A further object is to construct an improved sprayer which shall present a substantially identical resemblance in size and shape to a fountain pen. In this manner I am able to avoid attention to the user's infirmity.

A further object is to construct a sprayer which will deliver a predetermined measured quantity of fluid at each stroke.

A further object is to accomplish the foregoing objects in a relatively simple manner by providing a construction which will not easily get out of order.

My means of accomplishing the foregoing objects may be more fully comprehended by having reference to the accompanying drawings which are hereunto annexed and are a part of this specification, in which:

Fig. 1 is a vertical sectional view partly in elevation of my improved device;

Fig. 2 is a cross-section taken on the line 2—2 in the direction of the arrows;

Fig. 3 is a modified form of construction of the device shown in Fig. 1, the cap, plunger, and spring being omitted for sake of clarity;

Fig. 4 is a side elevation of a modified construction for an atomizer, the upper part being shown in section;

Fig. 5 is a sectional view taken on the line 5—5 in Fig. 4;

Fig. 6 is a sectional view taken on the line 6—6 in Fig. 5;

Fig. 7 is a sectional view taken on the line 6—7 in Fig. 5;

Fig. 8 is a view taken on the line 8—8 in the direction of the arrows, the cap being omitted;

Fig. 9 is a sectional view taken on the line 9—9 in Fig. 9;

Fig. 10 is a sectional view taken on the line 9—10 in Fig. 8, and

Fig. 11 is a fragmentary view of a modified form of my instrument some of the elements being omitted.

Similar reference numerals refer to similar parts throughout the specification.

As shown in Fig. 1 of the drawings my invention comprises a barrel 1. The barrel may if desired be made of a transparent plastic material so the amount of fluid may be seen. This barrel is provided with a cap 2, which is telescopically fitted to it. The cap 2 being pro-

vided with a clip 3 to attach the article to a user's garment. The lower portion of the barrel 1 is provided with a filler plug 4, which is shaped so as to provide an appearance common to many fountain pens. A fluid reservoir 5 is provided in

the lower part of the barrel 1, and a pump similar in function and operation to pumps which are known as "a displacement pump" is provided to eject the fluid from the reservoir 5. This pump is mounted in a body or member 6

which is telescoped into an upper end of the barrel 1. A cylinder 7 is formed in this body 6. In the cylinder 7, I mount a reciprocating piston 8, to the lower portion of which is secured a cup washer 9, which is mounted upon an extension

47 on the end of the piston 8. Below the piston 8 I mount a return spring 10, as illustrated, the lower portion of the spring 10 is broken away to show how its end is bent diametrically across the helix of the spring, the purpose of which 40 will be hereinafter described.

The piston 8 is provided with a piston rod 8' which telescopes an enlarged part 12 of a push rod 11. At the upper end of the push rod 11 I mount a suitable push button 19, for the convenient manipulation of the piston 8. At the lower end of the cylinder 7, I provide a cylindrical recess 13, smaller in diameter than the cylinder in which a ball check valve is located.

This valve consists of a ball 14, and a coil spring 15, adapted to cause the ball to contact the valve seat 16 formed at the bottom of the cylindrical recess 13. This serves to hold the valve normally closed. The lower end of the spring 10 serves as a stop for the upper end of the spring 15.

55 This end is preferably looped over the end of the

spring 10, where it extends across the diameter of the cylinder thereby forming a linkage to assist in assembly and disassembly of the parts. Preferably the spring 15 is formed of much stronger wire than the return spring 10. In this manner any deflection of the spring 10 is avoided. Adjacent the check valve 14—16 I mount a suction tube 17. This tube extends to a point a slight distance above the bottom of the fluid reservoir 5. The push rod 11 passes through a bushing 18, this bushing is provided with a flange 20, which is adapted to press a gasket 21 against the upper end of the body 6.

At the inner end of the bushing 18 is formed a chamber 22 which cooperates with a conoidal annulus 23 formed on the enlarged part 12 of the push rod 11. This forms a valve the function of which is to prevent oozing of the liquid, but will permit the entrance of air to replace the discharged liquid.

The enlarged part 12, of the push rod 11, should be made to fit loosely in the cylinder to allow air to pass to a port or passage 24, which provides communication with a space 25 formed by flattening the body 6, as clearly seen in Fig. 2.

This space 25 opens into the upper part of the reservoir 5, but should not extend above the barrel 1. This effectually prevents any leakage and thus protects the user's clothes.

A port or passage 36 leads to an enlarged lower part formed by a circumferential groove 34, in a longitudinal chamber 31 which is closed by a plug 29. This plug 29 should be fitted tightly so as to prevent any leakage. The plug 29 has an upwardly extending portion 30, which forms a seat 28 for a ball 26 of a secondary ball check valve. The ball is normally held to its seat 28 by a coil spring 27. The upwardly extending portion 30 of the plug 29 has an axial passage 32 which connects with the circumferential groove 34, formed on a reduced neck or stem 35. The groove 34 is in communication through port or passage 36, with the cylindrical recess 13, at the lower end of the cylinder 7. Any suitable means of tightening or removing the plug 29 may be employed. As illustrated it is a slot 37.

An upwardly extending tube 38 is fitted to the longitudinal passage 39. This tube is provided with a nozzle 39' which has a capillary size opening 40, through which the fluid is ejected.

In order to protect this minute opening 40, I form an inverted conoidal recess 41, in the end of the nozzle 39', and the opening 40 is at its apex. Thus should the user drop the device when the cap 2 is removed, no damage will result. The cap 2 carries means to seal the nozzle which consists of a sealing plunger 42, the lower end 43 of which is fitted to and coincides with the surface of the inverted conoidal recess 41. This sealing may be omitted if desired to reduce the manufacturing cost. The plunger 42 has a peripheral flange 46 which engages a member 45 fixedly mounted in the cap 2. A coil spring 44, serves to hold the end 43 yielding, but tightly against its seat in the conoidal recess 41.

It may be found desirable in some cases to employ the modified form of construction shown in Fig. 3, which is identical with that shown in Fig. 1, with the exception of certain details as follows: The tube 38, is omitted and the body 6, is extended upwardly in its place. The passage 39 extends throughout its length. As illustrated a concave longitudinal groove 19' is provided so the push rod 11, and push button 19, may be

freely reciprocated. A slightly different form of orifice 50 is shown in Fig. 3. Instead of the cylindrical recess 13, I form the cylinder 7 of the same diameter throughout. The shoulder upon which the spring rests is formed by a tube which is slightly fitted into the cylinder bore. The suction tube 17, is extended upwardly, its end forms a seat for the ball 14.

The operation is as follows:

10 The movement of the piston 8 upwardly due to the action of the spring 10 will draw the liquid past the check valve 14 into the cylinder 7. The push button is then depressed forcing the piston 8 downwardly. This closes the check valve 14 and the liquid (not shown) is forced through the port 36 into the annular chamber 34. The velocity of the liquid lifts the ball check valve 26, and the liquid enters the passage 39, where it travels up through the tube 38, and is ejected through the orifice in the nozzle, which preferably is of capillary size in the form of a fine mist or spray. The acceleration of the fluid in its passage operates to atomize it.

15 In Figures 4 to 10, I have shown a modified form of construction of my invention. In these figures the cap 2 is screwed to the body 51, instead of telescoping it. Obviously, any desired form of detachably securing the cap in place may be employed.

20 As shown the device is provided with both an air duct 52 and a liquid duct 53. These ducts are preferably of capillary size. In Fig. 5 I show the body 51 having an air cylinder 54, and the location of the two ducts 52 and 53, I also in this form provide two flat sides 55 and 56, formed on the body 51. These flats serve a double purpose, one—they materially reduce the dead weight of the device; and two—they increase the capacity of the reservoir. They extend from the lower end of the body 51 to a point adjacent the upper end of the barrel 57. A groove 58 provides communication between the air duct 52 and the space formed by the flat 55. This groove is formed in order that the displaced liquid in the reservoir may be replaced by air. The air will also operate to transmit some of the pressure produced by the pump onto the surface of the liquid, in this manner a hydrostatic pressure is produced which results in assisting the capillary action in tubes 59 and 60.

25 In the detail view Figure 6 is shown the air pump cylinder. In it is mounted a loosely fitting piston 62, which is carried by a push rod 61, the upper end of which has a push button 61' for convenient operation of the piston. The outer end of the push rod 61 carries a flexible cup washer 63, which abuts the piston 62. It is held in place by means of a washer 64, and a nut 65 mounted on threads 66, cut on the end of the push rod 61. The piston 62 is held normally retracted by a spring 67. The lower end of the cylinder 54, is closed by a plug 68, which has a central opening. An annular groove 69 is cut in the top of plug 68 to form a seat for the spring 67. The bottom of the plug 68 at the central opening is counter-bored to form a valve seat 70 for a ball 71 of a check valve. The ball 71 is held normally seated by means of a coil spring 73. This spring 73 is located in a socket 74 cut or cast in plug 75 screwed into the lower end of the body 51. This plug 75 is provided with a series of radial grooves which affords passage for the air to reach air duct 52 by means 30 of an air port or passage 71 cast or formed in

the body 51. Means may be provided to screw the plug 75 in place, as shown it consists of a screw driver slot, though obviously, any form of construction may be employed. A means of screwing plug 68 in place is provided by screw driver slot 72, as shown on the drawings. An air hole 79 for the air tube 80 is formed in the body 51.

A supplemental air suction hole 81, may be formed if there is not sufficient space intermediate the push rod 61, and the hole 82 in which it slides, otherwise hole 81 may be omitted.

In the detail view Figure 7, I have shown the manner in which the liquid duct may by-pass the air pump. In this view I have omitted the piston and related parts as they in no manner aid this view. I mount the liquid tube 59, in such a manner as to provide a passage therefrom to the liquid duct 53, which is in communication with a liquid hole 83, from which it passes to capillary tube 60. A spray member 85 is screwed into internal threads formed on the wall of a hole 86 in the nozzle 84. This member 85 is bored to form a Venturi tube 87, which has a seat 88 at its open end adapted to receive the end 43' of the sealing plunger 42'. The rim of the seat 88 will prevent damage to the Venturi tube should the user drop the device. An annular groove 89 is formed on the threaded part of member 85. This groove 89 communicates with the Venturi tube 87, through radial holes 90. As illustrated I show two of these, it may be found in practice that one is sufficient for the desired purpose. The top of the capillary tube 60 is fixed in nozzle 85, and is in communication with the annular groove 89 by means of connecting holes 91 and 92. The upper end of the air tube 80 is fastened to the nozzle 84.

A port or passage 93 provides communication between the air tube 80 and the hole 86, formed in the nozzle or spray member 85. It will be apparent to those skilled in the art that I provide a continuous air passage from inlet port 81 through the air pump, check valve, air port 77, air duct 52, air hole 79, air tube 80, air hole 93, tapered hole in Venturi tube 87 where it escapes. The air is bled from the pressure side of the system through groove 58 to the surface of the liquid in the reservoir where it replaces the exhausted liquid and provides for urging the liquid up the capillary tube 59 as hereinbefore explained.

It will also be obvious that there will be a continuous flow of liquid from the reservoir through capillary tube 59, liquid duct 53, hole 83, capillary tube 60, holes 91 and 92, holes 90 into Venturi tube 87, whence it will be discharged as spray in predetermined quantities per stroke.

The operation is similar to that of the form shown in Figs. 1 and 3. Pressure upon the push button 61' forces the air through the check valve up to air tube 80 and through the Venturi tube 87. At this point its increased velocity produces a partial vacuum in the holes 90. This acts to draw the liquid up the capillary tubes 59 and 60, into the Venturi tube 87.

When the liquid reaches this point the air blast forceably discharges it in a spray formed of minute globules. By releasing the pressure upon push button 61' the spring 67 operates to retract the piston 62 to its normal position. The movement of the piston in this direction causes the peripheral flange of the flexible cup washer to collapse and air will rush into the system because of the partial vacuum produced by the return of the piston to its normal position.

The operation may be repeated as often as desired.

In Figure 11 I have shown a simplified form of construction. In this form I move the ball check valve 26 from its seat 28 on the plug 29, to a seat 100, mounted in a sleeve 101. This sleeve is secured to the tube 38, which telescopes it, and may be fastened in any suitable and convenient manner. Below this ball-check valve 26 and mounted in the same sleeve 101 adjacent its end I mount the upper end 102 of a tube 103 which depends downwardly into the reservoir 5, a ball 104 exactly similar in function, manner of functioning and result produced to ball 14 shown in Figure 1, is fitted to a seat 105 formed on the end of tube 103.

I provide a port or passage 106 similar to the passage 36. Practice has shown this form is easier and less expensive to manufacture, than the one shown in the other figures.

Although I have described check valves of the ball type, it will be clear that any form of check valve may be employed.

The operation of this form is not materially different from the description herein before set forth. The upward movement of the piston will unseat the ball 104 and the liquid (not shown) will be drawn up into the lower part of the sleeve 101, and thence through the port or passage 106 into the cylinder 1. Depressing the push button 19 will force the liquid out through port 106, and will seat the ball 104 in the lower part of the sleeve, then will travel upwardly lifting the ball check valve 26 from its seat, thus permitting the liquid to enter the passage 39. It will then continue to travel upwardly and be ejected out the orifice in the nozzle. As explained this orifice is of such size as to cause the liquid to be ejected in the form of a fine mist or spray. Practice has shown that the acceleration of the liquid in its passage operates to atomize it where it travels up through the tube 38, and is ejected through the orifice in the nozzle, which preferably is of capillary size in the form of a fine mist or spray. The acceleration of the fluid in its passage operates to atomize it.

Should the user wish a larger proportion of liquid he may obtain this result by inverting the atomizer, this will cause the liquid to flow into the space formed by the flat 55, and hence through groove 58 into the air duct.

If pressure is then applied to the push button 61' the liquid will be ejected by the air pressure through the Venturi tube 87 in almost a solid stream. In this manner attaining the desired result.

It will be clear to persons who are skilled in the art that although I have described many specific details of construction, I do not wish thereby to limit myself thereto except as such limitations may appear in the hereinafter contained claims.

Having described my invention, what I regard as new and desire to secure by Letters Patent is:

1. In a device of the character described a barrel, a body portion therein which extends downwardly for a portion of the length of said barrel leaving a space below its lower end which constitutes a reservoir, said reservoir being adapted to hold fluid, said body portion having a cylinder formed therein, a reciprocating piston in said cylinder, means including a rod to actuate said piston, guide means for said rod, resilient means to hold said piston normally retracted, means formed in part on said piston and in part on said guide means adapted to admit air to the reser-

voir on a delivery stroke of the piston to replace fluid and to seal said cylinder when the piston is in returned position, a tubular conduit in said barrel offset but generally parallel to the axis of the cylinder in said body and extending downwardly to a region adjacent the lower end of said reservoir and upwardly to a region above the upper end of the body, a delivery nozzle at the upper end of said conduit having a discharge opening in substantial axial alignment with the axis of said barrel, said conduit being in fluid communication with the lower end of the said cylinder, and valve means in said conduit operatively responsive to reciprocation of the piston to pass fluid from the reservoir to the cylinder on an upward stroke of the piston and from the cylinder through the said nozzle on a downward stroke of the piston.

2. The combination of claim 1 including a cap member constructed and arranged to enclose said nozzle and the said barrel when the device is not in use and means in the cap adapted to seal the opening in the nozzle against leakage.

3. In a device of the character described a barrel, a body portion therein which extends downwardly for a portion of the length of said barrel leaving a space constituting a reservoir for a liquid medium, a cylinder in said body, a reciprocable piston therein, a push rod which extends upwardly beyond said body for actuating the piston, means to hold said piston normally in an upward retracted position, a sleeve member disposed within the barrel in substantial parallelism with the axis of the cylinder in the said

body, there being a fluid passageway between the interior of the sleeve at a medial region thereof and the interior of the cylinder at the lower end thereof, a conduit means extending from the lower end of the sleeve to the lower portion of the reservoir, a second conduit means extending upwardly from the sleeve and above the body portion adapted to mount a delivery nozzle, and valve means in the sleeve responsive to movement of the piston on its retracting stroke to pass fluid from the reservoir into the cylinder and on its pressure stroke to pass fluid from the cylinder through said upwardly extending conduit means.

4. The combination of claim 3 including means operatively associated with said piston to admit air to the reservoir on a pressure stroke of the piston and to seal the cylinder against leakage at the end of a retracting stroke of the piston.

EDWARD L. HADDEN.
